DESIGN FOR A COMBINATION WASHING MACHINE CABINET AND WRINGER HEAD

Oliver Leslie Earl, Salem, Ohio, assignor to Mullins Manufacturing Corporation, Salem, Ohio, a corporation of New York

Application April 23, 1936, Serial No. 62,256

Term of patent 7 years

To all whom it may concern:

Be it known that I, Oliver Leslie Earl, a citizen of the United States of America and residing at Salem, in the county of Columbiana and State of Ohio, have invented a new, original, and ornamental Design for a Combination Washing Machine Cabinet and Wringer Head, of which the following is a specification, reference being made to the accompanying drawing, forming part thereof.

The figure is a perspective view of one side of a combination washing machine cabinet and wringer head showing my new design, the other side being the same as the side shown.

A dominant feature of my design resides in the walls of the base, which form substantially the lower half of the cabinet, being in concentric alignment and flush with the walls of the tub, which forms substantially the upper half of the cabinet.

I claim:

The ornamental design for a combination washing machine cabinet and wringer head as shown and described.

OLIVER LESLIE EARL.
